ADJUSTABLE STOP FOR LEVERS ON EDGERS

Filed Nov. 10, 1925

Fig. 2.

Patented June 15, 1926.

1,589,197

UNITED STATES PATENT OFFICE.

JAMES FRANCIS McCARROLL, OF BATON ROUGE, LOUISIANA.

ADJUSTABLE STOP FOR LEVERS ON EDGERS.

Application filed November 10, 1925. Serial No. 68,174.

This invention relates to improvements in stops for levers, and it consists of the constructions, combinations and arrangements herein described and claimed.

5 An object of the invention is to provide adjustable notch blocks or stops which are of such construction that relative adjustments are readily made, thereby to suit the various throws of the shifting or operating lever of a saw mill edger with which lever the stops are associated.

10 Other objects and advantages appear in the following specification, reference being had to the accompanying drawing, in 15 which—

Figure 1 is a side elevation of a portion of a rest bar upon which a pair of the improved stops is mounted, the associated operating lever being shown in section.

20 Figure 2 is a cross section taken on the line 2—2 of Figure 1.

A brief introduction will acquaint the reader with the use of the adjustable notch blocks or stops. An edger as used in saw 25 mill work, accomplishes the purpose of trimming either one or both of the longitudinal edges of a rough board. The edger saw is capable of either deflecting or sliding motion to accomplish the purposes of the 30 edger, and this motion is obtained by the rocking or shifting of an operating lever 1 which is but fragmentarily illustrated in the drawing.

In Figure 1 the rest bar 2 is fastened 35 rigidly on the frame of the edger, and extends crosswise thereof. The reader is supposed to be looking in the direction of the saw, and inasmuch as the operating lever 1 extends in that direction, it is shown in section. In Figure 2, the lever 1 is supposed to extend toward the saw at the left. The lever has a latch piece 3 securely riveted or otherwise secured thereto at 4.

Consider now the invention. Use is made 45 of a number of notch blocks or stops, the number actually employed depending upon the width of the edger and the range of movement of the lever 1. It is intended that the lever shall be held at any point 50 within the range of its adjustment. An edger may also have a plurality of movable saws, consequently an equal plurality of levers will be employed. Each lever will have an appropriate number of stops, but the invention can be easily and fully understood by considering only a pair of the stops

as herein disclosed. Inasmuch as all of the stops are identical, the description of one will suffice for all, and corresponding reference numerals apply to similar parts.

50 The notch block or stop 5 has a shape substantially like the letter C (see the one at the left in Figure 2) and this being the case includes the flanges 6 which together with the main body of the stop produce a channel 65 7 in which the rest bar 2 is received. The upper flange 6 is interrupted to produce a notch 8, and it is in the notches 8 of the stops involved that the latch piece 3 is set when the lever has been shifted.

70 A slot 9 receives the stud 10 by means of which the notch block or stop 5 is clamped in position upon the rest bar. The stud is screwed into the rest bar, and upon being loosened with a wrench permits such adjustment upon the rest bar as will suit the desired throw of the lever 1. The stop is reinforced at 11 around the slot.

75 The operation is readily understood. The notch blocks or stops 5 are applied to each 80 of the opposite sides of the stationary rest bar 2 the number depending upon width of edger and arc of lever so that the stops assume confronting positions. This relationship of the stops is important should it ever 85 be required that the stops be adjusted toward each other (see Fig. 1) in order to bring the notches 8 closer together. Under this circumstance it is conceivable that the 90 stops may assume overlapping positions and were they located on the same side of the rest bar 2 the extent to which they might be adjusted toward each other would soon be limited by the engagement of adjacent edges. The reader will soon understand 95 this by a brief inspection of Figure 1.

The range of adjustment afforded by the slot 9 accommodates the longest adjustable movement of the notch block or stop 5. It is readily seen that as the lever is swung to 100 adjust saw held between guide blocks on opposite end for boards of various widths the latch piece 3 is let down into the nearest notch 8 to thereby hold the lever in position.

105 I claim:—

1. In combination with the stationary rest bar of an edger, adjustable notch blocks or stops applicable to opposite sides of the bar in confronting positions for the purpose of 110 giving each setting of lever an independent adjustment, and means for holding the stops

in place on said rest bar and permitting relative adjustment of the stops including an adjustment in overlapping position, said last adjustment being permissible by the location of the stops on opposite sides of said bar.

2. In combination with the stationary rest bar and shiftable operating lever of an edger, a number of notch blocks or stops, each being applicable to opposite sides of the bar, and means by which the stops are adjustable to accommodate various throws of the lever, said adjustments being possible to obtain an overlapping relationship of the stops but without one stop interfering with the other.

3. In combination with the fixed rest bar

and operating lever of an edger, said lever having a latch piece, a number of notch blocks or stops applicable to opposite sides 20 of the bar each having a notch for the reception of the latch piece, and means permitting independent and nonconflicting adjustment of the stops on the respective sides of the bar properly positioning the notches 25 to suit various throws of the lever.

4. A stop for the purpose described comprising a body having flanges producing a channel to receive a support including a rest bar, said body having a slot to receive securing means, and said body being reinforced around the slot, one of said flanges being interrupted to produce a notch.

JAMES FRANCIS McCARROLL.
